UNITED STATES PATENT OFFICE

135,807

DESIGN FOR AN APRON

Emma E. Koehler, Elmhurst Gardens, Ill.

Application November 11, 1942, Serial No. 108,749

Term of patent 3½ years

To all whom it may concern:

Be it known that I, Emma E. Koehler, a citizen of the United States, residing at Elmhurst Gardens, in the county of Du Page and State of Illinois, have invented a new, original, and ornamental Design for Aprons, of which the following is a specification, reference being had to the accompanying drawing, forming part thereof.

The figure is a front elevational view of an apron showing my new design. The back of the apron is conventionally plain.

I claim:

The ornamental design for an apron, as shown and described.

EMMA E. KOEHLER.
